UNITED STATES PATENT OFFICE.

WILLIAM M. HAMILTON, OF PITTSBURG, PENNSYLVANIA.

STEAM-BOILER.

SPECIFICATION forming part of Letters Patent No. 484,786, dated October 18, 1892.

Application filed September 28, 1891. Serial No. 407,061. (No model.)

To all whom it may concern:

Be it known that I, WILLIAM M. HAMILTON, a citizen of the United States, residing at Pittsburg, in the county of Allegheny and State of Pennsylvania, have invented certain new and useful Improvements in Steam-Boilers; and I do hereby declare the following to be a full, clear, and exact description of the invention, such as will enable others skilled in the art to which it pertains to make and use the same, reference being had to the accompanying drawings, which form a part of this specification.

My invention relates to an improved steam-boiler; and it consists in certain details of construction and combination of parts, as will be fully described hereinafter.

In the accompanying drawings, Figure 1 is a central side sectional elevation of my improved steam-boiler which is constructed in accordance with my invention. Fig. 2 is a front sectional elevation of the same, taken at the rear of the bridge-wall on the line X X. Fig. 3 is an elevation of the front head, showing the position of the man-heads.

To construct a steam-boiler in accordance with my invention, I provide a cylindrical tube 1 of a large diameter and of a suitable length and connect each end of the same to a front and rear chamber 2 and 3. These chambers 2 and 3 are cylindrical in cross-section and are provided with convex heads 4 and inner flanged plates 5 and the said plates attached to the above-described tube 1 above the center. Each of these chambers 2 and 3 is provided with man-heads 6 for the purpose of cleaning the boiler. Beneath this tube 1 and connected to the inner flanged plate of each chamber 2 and 3 is a series of tubes 8, which are exposed to the fire. Arranged in the front chamber 2 and above the water-line is an imperforate plate or deflector 9, one end of which is secured to the outer wall of the chamber 2 below the top thereof, from which point it extends incliningly over the mouth of the exit-pipe 10 toward the tube 1, so that the steam generated in the front chamber is caused to travel around the inner edge of the deflector before entering the steam-outlet pipe 10.

This boiler, constructed as described, is arranged in a suitable setting in an inclined

position, being elevated at the front and the rear brought to within a short distance of the general level of the setting, and the 55 said setting consisting of the two outside walls 11 to inclose and support the boiler, a fire-chamber 12, and bridge-wall 13. The grate-bars 14 are also arranged in an inclined position corresponding in inclination 60 to the boiler above described. The location of the man-heads in the front chamber 2 is such that all the small water-tubes 8 may be cleaned, repaired, or replaced from the front of the boiler. Located within the large 65 tube 1 is a conical-shaped water-filter 15, having an open front end arranged slightly below the water-level. At the rear end of this filter 15 is connected a pipe 16, which leads out of the boiler through the rear wall of the 70 setting and is provided with a valve or cock (not shown) of ordinary construction. The feed-water pipe 17 enters this filter 15 at the front or largest end, and any sediment or heavy substance will settle in the exit-pipe 75 16 and may be removed therefrom by opening the said valve at the outer end of the pipe 16. The position and construction of this filter 15 are such that the same may be used as a surface blow-off, and will be found 80 useful for this purpose when the surface of the water becomes covered with froth or vegetable matter.

By the use of this steam-boiler a large amount of surface is exposed to the fire, therefore saving fuel and generating steam quickly.

The general construction and arrangement of this steam-boiler may be altered and changed. Therefore I do not confine myself to the exact construction shown and described. 90 The chambers may be made triangular or oval in cross-section in place of cylindrical, as above described, without departing from the spirit of my invention.

Having thus described my invention, what 95 I claim, and desire to secure by Letters Patent, is—

1. A steam-boiler consisting of the chambers located at each end, the front chamber having an exit-pipe leading from its top, a 100 pipe or tube connecting the said chambers above the centers, a series of small tubes or pipes connecting the chambers beneath the said tube, and a deflector in the front cham-

- ber, said deflector consisting of an imperforate plate secured at one end to the outer wall of the chamber below the top thereof, but above the water-line and extending thence 5 toward the tube 1 and beyond the mouth of the exit-pipe, said deflector thereby compelling the steam to travel around its innermost edge on its way to the exit-pipe, substantially as described.
- 10 2. A steam-boiler set in an inclined position and having a grate correspondingly inclined, said boiler having chambers at each end and pipes connecting said chambers, a portion of which pipes is exposed directly 15 to the fire, the front chamber having an exit-pipe and a deflector, said deflector consisting

of an imperforate plate secured at one end to the outer wall of the chamber below the top thereof, but above the water-line, and extending thence inclining to a point beneath and 20 beyond the mouth of the exit-pipe, said deflector thereby compelling the steam to travel around its innermost edge on its way to the exit-pipe.

In testimony that I claim the foregoing I 25 hereunto affix my signature this 3d day of September, A. D. 1891.

WILLIAM M. HAMILTON. [L. S.]

In presence of—
CHARLES LARGE,
M. E. HARRISON.
